UNITED STATES PATENT OFFICE.

FRANK REAUGH, OF OAK CLIFF, TEXAS.

PUMP OR MOTOR.

Application filed July 18, 1923. Serial No. 652,227.

To all whom it may concern.

Be it known that I, FRANK REAUGH, a citizen of the United States, and resident of Oak Cliff, in the county of Dallas and State of Texas, have invented certain new and useful Improvements in Pumps or Motors, of which the following is a specification.

This invention relates to that type of machine in which a rotary movement of the operating parts is caused by or causes a positive movement of the fluid, as for instance in a motor or pump. The machine may be driven from outside power and transfer a fluid, as in a vacuum pump, compressor, blower, or fluid propelling apparatus, or it may receive the fluid under pressure and be driven thereby so as to serve as a prime mover or motor, the motive fluid being gas, steam, water or other medium.

20 In my improved construction a plurality of piston members are mounted on a rotor so as to rotate about their own individual axes, as well as being carried bodily around the axis of the rotor.

25 One important feature of my improved construction is the elimination of the core or other stationary or rotating central part around which the pistons or blades revolve. I accomplish this by employing two pistons each of which has its working surfaces generated by the arc of a circle whose radius is equal to the diameter of the disk circle upon which the movement operates.

35 As another feature I make the pistons of such proportions and so positioned in respect to each other that one-half the sum of the length and thickness of a piston member is equal to the diameter of the circle in which the axes of the pistons travel.

40 As another distinguishing feature, the pistons which rotate about their own axes in a rotor which carries said pistons bodily about its axis, as in my prior Patent 1,101,329, are so designed as to be continuously in contact with each other, the contact being a sliding rather than a rolling one.

45 In the accompanying drawings I have illustrated one embodiment of my invention. In these drawings:

50 Fig. 1 is a central longitudinal section, said section being taken substantially on the line 1—1 of Fig. 4.

55 Figs. 2, 3 and 4 are vertical transverse sections on the lines 2—2, 3—3, and 4—4 respectively of Fig. 1, and

Figs. 5 to 9 inclusive are views similar to a

portion of Fig. 4, but showing diagrammatically successive positions taken by the rotor during the rotation thereof.

In the construction illustrated the rotor 60 includes a pair of disks 10 spaced in axial alignment and rigidly connected by a pair of frame members 11 substantially triangular in cross-section. The two disks serve to support two pistons 12 which have oppositely projecting shaft parts 13 journaled in the two disks to permit rotation of the pistons about axes parallel to the common axis of the two disks, which is the axis of the rotor. The two frame members 11 are 65 each substantially triangular in cross section, and are disposed upon diametrically opposite sides of the axis of the rotor. The two pistons are also disposed upon diametrically opposite sides of the axis of the 70 rotor, and midway between the two frame members 11. The two frame members have their outer surfaces in arcs of the same circle whose center is coincident with that of the axis of the rotor. Each frame member has 75 two inwardly facing curved faces intersecting at an angle, and in the arcs of circles of the same diameter, and whose centers are coincident with the axes of the pistons.

80 Each piston has two opposite curved working faces intersecting at the ends of the piston, and in the arcs of circles having the same radii. The radius of curvature of both working surfaces of both pistons is exactly equal to the distance between the 85 axes of the two pistons. Also the sum of one-half the maximum radius of the piston and one-half the minimum radius is equal to this same distance between the axis of the two pistons. From the foregoing it necessarily follows that each piston as it rotates will have its ends move in sliding contact with the inner surface of the two frame members 11, and that by properly controlling the movement of the two pistons they 90 may be kept in contact with each other at all times during their simultaneous rotation about their respective axes.

95 As a preferred means of effecting the rotation of the pistons and properly timing such rotation in respect to the rotation of the rotor, I provide gearing shown particularly in Figs. 1, 2 and 3. One of the disks 10 forming one end of the rotor is provided with a shaft 14 extending outwardly from the outer surface thereof. The shafts 13 of the pistons project through the same disk, and their outer 100 105 110 115

ends are provided with pinions 15. These pinions both mesh with a pinion 16 which is mounted on but rotatable in respect to the shaft 14. The pinion 16 is rigidly connected to a pinion 17 and the latter meshes with a pinion 18 on a shaft 19 mounted in stationary bearings. The shaft 19 carries a pinion 20 which meshes with a pinion 21 which is keyed or otherwise rigidly secured to the shaft 14. The pinion 21 is larger than the pinion 20, and the pinion 18 is larger than the pinion 17. As the pinion 21 is positively rotated with the shaft, it turns the pinion 20 at higher angular velocity and the pinion 18 which is rigid with the pinion 20, turns the pinion 17 at still higher angular velocity. Thus the pinion 16 which is rigid with the pinion 17, turns in the same direction as the rotor, but at higher speed, and the pistons are rotated on their axes in the reverse direction. The relative pitch diameters of the several pinions is such that the speed of rotation of the pinions in the rotor and about their own axes is one-half that of the rotor and in the reverse direction, but the net effect is that the pistons rotate in the same direction as the rotor, but at half speed, when considered in respect to a fixed point. In other words, during a complete revolution of the rotor each piston will rotate in the rotor through 180° about its own individual axis.

The rotor may be mounted in a suitable casing having casing wall parts for engaging with the peripheries of the disks, and with the other rotor parts between an inlet and an outlet. As shown, the casing includes a pair of end casing sections 22 and 23 each having circular apertures receiving the corresponding rotor disk 10 and engaging with the periphery of the latter. The engagement between the periphery of each disk and the casing is provided with packing or is otherwise formed to prevent leakage. The casing section 22 has an end wall portion 24 spaced from the outer surface of the corresponding disk 10 and providing a journal for the shaft 25 rigidly connected to said disk 10. This shaft may serve as the main drive or driven shaft of the apparatus, or the shaft may be omitted and the shaft 14 at the other end serve this purpose. The opposite end casing section 23 forms a housing for the gearing, and has a transverse partition or flange 26 having journals for the shafts 14 and 19. The outer end wall 27 may be detachable and may also have a second journal for the shaft 14. The various bearings may be lubricated in any suitable manner, as for instance by the delivery of oil through a central passage in the shaft 14, and from this shaft through radial passages to the bearings of the several gears and other rotating parts.

Between the two end casing sections 22

and 23 there is provided a peripheral casing section 28 encircling the rotor, and having ports 29 and 30 serving as inlet and exhaust ports. The direction of rotation of the rotor will determine which port serves as the inlet 70 and which as the outlet.

The peripheral casing is eccentric in respect to the axis of the rotor. The surface 31 at one side of the rotor is theoretically a portion of a limacon curve, and its maximum distance from the axis of the rotor is equal to the maximum radius of the piston plus the radius of the circle in which the axis of the piston travels. In practice this curve may be made a true circle with a 80 radius slightly smaller than the maximum distance above referred to, and having its center eccentric to that of the rotor and to the proper distance toward said surface from said rotor axis. In fact, the inner 85 surface of the entire casing section 28 may be machined as a true circle, and a filler or liner piece 32 inserted diametrically opposite to the surface 31 and having its outer surface in the same circle as the surface 31, 90 and the major portion of its inner surface in the circle of the outer surface of the rotor frame members 11.

By thus constructing the parts, all surfaces of the casing may be made either 95 plane or arcs of true circles, and the same applies to all portions of the several parts of the rotor. The machining operations are thus comparatively simple and very much less expensive than that involved in machining curved surfaces other than arcs of circles.

In Figs. 5 to 9 inclusive I have illustrated five of the successive positions which the parts take during a half revolution of the 105 rotor. It will be noted that the pistons are always in contact with each other, and that one or the other is always in contact with the surface 31. Also, the liner member 32 is always in contact with either a piston or a frame member 11 of the rotor, and that the frame members 11 never engage with the surface 31. The rotor is shown as turning in a clockwise direction from the position shown in Fig. 5 through the successive 110 positions illustrated in Figs. 6 to 9 inclusive, and it will be noted that each piston also rotates about its own axis in a clockwise direction in respect to a fixed point, and at one-half the angular velocity of the rotor. 115

In designing an apparatus, any given dimension may be selected, as for instance, the desired distance between the axes of the pistons; this dimension will also be the radius of curvature of the sides of the pistons. The square root of one-half the square of that dimension will give the maximum radius of the piston and said dimension minus the maximum radius will give the 125 minimum radius of the piston. The center 130

of curvature of the surface 31 of the casing will be offset from the center of the rotor to a distance about equal to one-half the minimum radius of a piston.

5. Although the gearing shown is a simple and efficient means for imparting to the pistons the desired movement during the rotation of the rotor, or imparting rotation to the rotor by fluid pressure on the pistons, 10 it will be apparent that other forms of gearing or other means might be employed for securing this result. For instance, I may employ cam means of the same general character as that shown in my prior Patent 15 1,101,329, but of appropriate design to give the desired piston rotation.

Having thus described my invention, what I claim as new and desire to secure by Letters Patent is:

20 1. A rotor for pumps, motors and the like, including a rotatable part and a pair of piston members having their axes carried thereby, said members being bodily movable around the axis of the rotor and rotatable 25 simultaneously on their own respective axes, and maintained constantly in contact with each other.

2. A rotor constructed as defined in claim 1, in which the pistons are caused to turn 30 about their axes in the rotor at one-half the angular velocity of the rotor itself.

3. A rotor for pumps, motors and the like, including a rotatable part and a pair of piston members having their axes carried thereby in diametrically opposite positions in respect to the axis of the rotor, said piston members being bodily movable 35 around the axis of the rotor and rotatable simultaneously in the reverse direction about their own respective axes in the rotor, and having constant sliding contact with each other.

4. A rotor for pumps, motors and the like, including a rotatable part, a pair of piston members having their axes carried thereby, said members being bodily movable 45 around the axis of the rotor and rotatable simultaneously in the reverse direction about their own axes, and intermediate 50 members each having the two adjacent portions of their inner surfaces intersecting at an angle, and disposed in the arcs of circles having the axes of the pistons as centers.

5. A rotor for pumps, motors and the like, including a rotatable part, a pair of piston members having their axes carried thereby, said members being bodily movable 55 around the axis of the rotor and rotatable simultaneously about their own axes, and intermediate members each having the two adjacent portions of their inner surfaces intersecting at an angle, and disposed in the arcs of circles having the axes of the pistons as centers.

6. A rotor for pumps, motors and the

like, including a rotatable part, a pair of piston members having their axes carried thereby, said members being bodily movable around the axis of the rotor and rotatable simultaneously about their own respective 70 axes, and intermediate members substantially triangular in cross-section and disposed at diametrically opposite points, and midway between said piston members.

7. A rotor for pumps, motors and the like, including a rotatable part, a pair of piston members having their axes carried thereby, said members being bodily movable around the axis of the rotor, and rotatable simultaneously about their own respective 75 axes, the axes of said rotors being parallel to that of the rotor and in diametrically opposite positions, and a pair of rotor frame members substantially triangular in cross-section, and each having its two inner intersecting surfaces in the arcs of circles having the axes of the pistons as centers and of the same radius as the maximum radius of said pistons.

8. A rotor for pumps, motors and the like, including a rotatable part, a pair of piston members having their axes carried thereby, said members being bodily movable around the axis of the rotor and rotatable simultaneously about their own respective axes, the axes of said rotors being parallel to that of the rotor and in diametrically opposite positions, the distance between the axes of the pistons being equal to one-half of the maximum radius plus 100 one-half the minimum radius of a piston.

9. A rotor for pumps, motors and the like, including a rotatable part, a pair of piston members having their axes carried thereby, said members being bodily movable around the axis of the rotor and rotatable simultaneously about their own respective axes, the axes of said rotors being parallel to that of the rotor and in diametrically opposite positions, the pistons being of 105 such size and shape that they are continuously in contact with each other.

10. A rotor for pumps, motors and the like, including a rotatable part, a pair of piston members having their axes carried thereby, said members being bodily movable around the axis of the rotor and rotatable simultaneously about their own respective axes, the axes of said rotors being parallel to that of the rotor and in diametrically opposite positions, the pistons being 115 symmetrical and each having its opposite working surfaces in the arcs of intersecting circles the radii of which are equal to the distance between the axes of the pistons.

11. A rotor for pumps, motors and the like, including a rotatable part, a pair of piston members having their axes carried thereby, said members being bodily movable around the axis of the rotor and rotat-

able simultaneously about their own respective axes, the axes of said rotors being parallel to that of the rotor and in diametrically opposite positions, the distance between the axes of the pistons being equal to one-half of the maximum radius plus one-half of the minimum radius of a piston, and substantially triangular frame members disposed at diametrically opposite points between said pistons, and each having a pair of intersecting inner surfaces with which the portions of the pistons of maximum radius engage.

12. A rotor for pumps, motors and the like, including a rotatable part, a pair of piston members having their axes carried thereby, said members being bodily movable around the axis of the rotor and rotatable simultaneously about their own respective axes, the axes of said rotors being parallel to that of the rotor and in diametrically opposite positions, the pistons being of such size and shape that they are continuously in contact with each other, and substantially triangular frame members disposed at diametrically opposite points between said pistons, and each having a pair of intersecting inner surfaces with which the portions of the pistons of maximum radius engage.

13. A rotor for pumps, motors and the like, including a rotatable part, a pair of piston members having their axes carried thereby, said members being bodily movable around the axis of the rotor and rotatable simultaneously about their own respective axes, the axes of said rotors being parallel to that of the rotor and in diametrically opposite positions, the pistons being symmetrical and each having its opposite working surfaces in the arcs of intersecting circles, the radii of which are equal to the distance between the axes of the pistons, and substantially triangular frame members disposed at diametrically opposite points between said pistons, and each having a pair of intersecting inner surfaces with which the portions of the pistons of maximum radius engage.

14. A pump, or motor, including a casing having an inlet, an outlet, and a peripheral wall portion, and a rotor eccentrically mounted within said casing and having triangular frame parts adapted to engage with the casing wall nearest the axis of the rotor and pistons rotatable about their own axes in the rotor and adapted to engage with the casing wall and with said frame parts.

15. A pump or motor, including a casing having an inlet, an outlet, a rotor eccentrically mounted within the casing and having pistons bodily carried thereby and rotatable simultaneously about their respective axes in the rotor, and triangular frame

members forming parts of the rotor and adapted to engage in succession with the parts of the casing nearest to the axis of the rotor, the maximum radius of each piston being greater than the distance between the axes of the pistons.

16. A pump or motor, including a casing, a rotor mounted therein and having a plurality of pistons carried thereby and rotatable about their respective axes which are parallel to the axis of the rotor, a shaft rotatable about a fixed axis parallel to the axis of the rotor, gearing between said shaft and said rotor, and gearing between said shaft and said pistons for imparting to the latter rotation about their respective axes during the rotation of the rotor.

17. A pump or motor constructed as defined in claim 16, in which the gearing is so proportioned that the pistons rotate about their axes in the rotor at one-half the angular velocity of the rotor itself about its axis.

18. A pump or motor constructed as defined in claim 16, in which the gearing is so proportioned that the pistons rotate about their axes in the rotor at one-half the angular velocity of the rotor itself about its axis, and in the opposite direction.

19. A pump or motor including a casing having inlet and outlet ports, a rotor mounted to revolve within the casing, pistons carried bodily by said rotor, a pinion connected to said rotor, a gear member coaxial with said rotor and rotatable in respect thereto, an auxiliary shaft having two pinions, one meshing with the first mentioned pinion and the other meshing with said gear member, and each of said pistons having pinions meshing with said gear member, whereby said pinions are rotated about their own axes during their bodily movement about the axis of the rotor.

20. A pump or motor constructed as defined in claim 19, in which the relative sizes of the pinions are such that the direction of rotation of the pistons in the rotor is opposite to that of the direction of rotation of the rotor itself.

21. A pump or motor constructed as defined in claim 19, in which the relative sizes of the pinions are such that the direction of rotation of the pistons in the rotor is opposite to that of the direction of rotation of the rotor itself, and the speed of rotation of the pinions is equal to one-half that of the rotor.

22. A pump or motor having a casing a rotor eccentrically mounted therein and having a pair of pistons rotatable about their respective axes in the rotor, the axes of the pistons being upon opposite sides of the axis of the rotor and the pistons having their opposite working faces in the arcs of intersecting circles whose radii are equal

to the distance between the axes of the pistons, said casing having an inlet, an outlet, a wall part between the inlet and outlet on one side spaced from the axis of the rotor to a distance approximately equal to half the distance between the axes of the pistons plus half the minimum radius of a piston, and a wall part diametrically opposite to the first mentioned wall part and

spaced from the axis of the rotor to a distance substantially equal to one-half the distance between the axes of the pistons plus one-half the maximum radius of a piston.

Signed at Dallas, in the county of Dallas and State of Texas this eleventh day of July A. D. 1923.

FRANK REAUGH.
